EARTH ANCHOR

Filed Jan. 4, 1935

UNITED STATES PATENT OFFICE

2,029,740

EARTH ANCHOR

Max Rosner, Chicago, Ill., assignor to General
Outdoor Advertising Co., Inc., Chicago, Ill., a
corporation of New Jersey

Application January 4, 1935, Serial No. 420

3 Claims. (Cl. 189—92)

My invention relates to earth anchors, and is particularly concerned with improvements in earth anchors of the type which are installed by forming a hole to place the anchor and then spreading the anchor to prevent further sinking or raising of said anchor from the formed hole.

One of the objects of my invention is the provision of an improved commercial form of anchor of the class described, which results in greater strength of the installation with less labor and expense.

Another object of my invention is to provide an anchor that cannot be withdrawn without offering resistance equivalent to the pull for which it was designed.

Another object of my invention is the easy manner in which the pipe or guy rod can be salvaged by unscrewing said pipe or rod from the anchor.

Another object of my invention is the multiplicity of resisting leaves can be varied in shape or number in accordance with the nature and resistance of ground.

Another object of my invention is its rigidity before being formulated in the hole and the simplicity with which it permanently assumes its final shape.

Other objects and advantages will be apparent from the following description and the accompanying drawing, in which similar characters of reference indicate similar parts throughout the several views.

Referring to the single sheet of drawings accompanying this description:

Fig. 1 is a vertical sectional view taken through the earth at a plane determined by the guide and driving pipes and the hole which was dug for the anchor, showing the improved mode of installation;

Fig. 2 is a sectional view similar to Fig. 1, showing the anchor driven down by the driving pipe;

Fig. 3 is a sectional view similar to Figs. 1 and 2, with the anchor in final position, the driving pipe withdrawn and the earth in place;

Fig. 4 is a plan view of the anchor in its spread position;

Fig. 5 is a sectional view taken on the line 5—5 of Fig. 4;

Fig. 6 is a detail view of one of the anchoring leaves, and

Fig. 7 is a detail view of a modified form of an anchor leaf.

Referring to Figs. 1 to 3 indicates in its entirety a leaf expanding anchor 10, consisting of upper and lower mounting plates 12 and 14. Inter-

posed between the mounting plates 12 and 14 are four expanding leaves 16 which are bent at their midsections. Threadedly attached at 18 to the lower mounting plate 14 is a guy pipe or rod 20, the upper plate 12 has a drilled guide hole 22 of a larger annular diameter than the guy pipe 20, to permit free movement of the plate 12 downwardly when the anchor is being driven by a driving pipe 24.

The guy pipe 20 must be of a desirable length 10 and without any projections in order to permit the driving pipe 24 to either slidably or loosely fit over said guy pipe and extending a foot or more higher than guy pipe 20, thus providing ample clearance when striking at the end of the driving 15 member, with a sledge or any other appropriate driving tool spreading the anchor 10 into its proper expandable position.

The anchor 10 is adapted to fit easily into the drilled hole 26 of Fig. 1, the earth in the walls 20 being relatively compact allowing the anchor to drop or slide to the required depth, depending solely whether the hole is a vertical one or one drilled at an angle. The expanding anchor 10 is preferably attached to the guy pipe 20 before 25 entering the drilled hole and then is lowered to the bottom 28 of the drilled anchor hole. The anchor is now in the proper position to be expanded, which necessitates the use of the driving pipe 24. Fig. 2 illustrates the expanded forma- 30 tion of the anchor after the driving pipe 24 has been struck by an appropriate driving tool and the manner in which the anchoring leaves 16 have entered into the undisturbed firm earth. By 35 rotating the guy pipe 20 in a clockwise direction after the driving pipe 24 has been removed the anchoring leaves 16 bite into more substantially undisturbed ground, thus firmly anchoring the same.

The anchoring leaf 16, of which Fig. 6 is a detail, has at both of its extremities two retaining lugs 30 which in turn fit into corresponding rectangular slots 32 formed in plates 12 and 14. In the center of the leaves 16 are cut out relief slots 34 which naturally, when slightly bent as indicated at 36 of Fig. 1, will be the first and only place the leaf will bend because of the cut out relief 34, and the beforementioned break 36. In the assembly of the leaves to the top and bottom plates 12 and 14 when the anchoring leaves are 40 spread in their slight outward direction (in order to be in proper position so as to bend in an outward horizontal direction when struck by the driving pipe), the projecting lugs 30 bend sufficiently 45 in order to get a binding grip in the upper 50 55

and lower plates 12 and 14 and make the anchor 10 a complete unitary device without any other forming operations.

The condition of the earth will govern the size, shape and number of leaves. There may be from 5 two leaves to eight, or even more, and the leaves may also be of a tapered shape as shown in Fig. 7, which will give the anchor 10 a greater resistible area, but conditions such as these will occur 10 only when the earth is of a very soft nature.

Whenever the necessity arrives for the tearing down of the job for which the anchor 10 is used, the salvaging of the guy pipe 20 will be a very simple 15 matter and will not require any cutting or digging to loosen it from the anchor 10. By merely turning the guy pipe 20 in a counter-clockwise direction, it will be unscrewed from the plate 14 then pulled through the upper plate 12, and then finally withdrawn from the hole.

It will thus be observed that I have invented an 20 earth anchor having means for securely positioning the anchor on a guy pipe during the installation of the anchor, the formation of the anchor by a driving pipe, and my invention also permits the release of the guy pipe when it is desired to 25 abandon the anchor.

While I have illustrated a preferred embodiment of my invention, many modifications may be made without departing from the spirit of the 30 invention, and I do not wish to be limited to the precise details of the construction set forth, but desire to avail myself of all changes within the scope of the appended claims.

Having thus described my invention, what I claim as new and desire to secure by Letters Patent of the United States is:

1. An earth anchor for a guy member comprising an upper plate and a lower plate mounted 5 on said guy member, each having a peripheral series of openings, a series of leaves each having a reduced lug at each end, and each lug entering an opening in one of said plates, said leaves being initially bent at its midpoint so as to bow outwardly and being weakened at said point so that said leaves collapse outwardly when the plates are caused to approach.

2. In combination, a guy member, an earth anchor mounted thereon comprising a lower plate 15 immovably mounted on the guy member, an upper plate mounted for free sliding movement on the guy member, said plates have corresponding peripheral openings, and leaves having reduced lugs at opposite ends entered into corresponding openings in said plates, said leaves being initially bent at their mid-point so as to project outwardly.

3. In combination, a guy member, an earth anchor mounted thereon comprising a lower plate 20 immovably mounted on the guy member, an upper plate mounted for free sliding movement on the guy member, said plates having corresponding peripheral openings, and leaves having reduced lugs at opposite ends entered into corresponding openings in said plates, said leaves being weakened at 25 said mid-point.

MAX ROSNER.
